US0D1114029S

(12) **United States Design Patent** (10) **Patent No.:** **US D1,114,029 S**
(45) **Date of Patent:** **** Feb. 17, 2026**

(54) **CAMERA**

(71) Applicant: **Teledyne FLIR Commercial Systems, Inc.**, Goleta, CA (US)

(72) Inventor: **Thomas Lewis Pethick**, Vancouver (CA)

(73) Assignee: **Teledyne FLIR Commercial Systems, Inc.**, Goleta, CA (US)

(**) Term: **15 Years**

(21) Appl. No.: **29/793,671**

(22) Filed: **Jan. 10, 2024**

(51) **LOC (15) Cl.** **16-01**

(52) **U.S. Cl.**

USPC **D16/218**

(58) **Field of Classification Search**

USPC D16/200, 202, 203, 219

CPC G03B 17/02; G03B 19/18; G06V 20/52

(57) **CLAIM**

The ornamental design for a camera, as shown and described.

DESCRIPTION

FIG. 1 is a front, left, and top perspective view of the camera embodying the new design and illustrated with an example lens barrel coupler suitable to couple to a lens;

FIG. 2 is a front perspective view thereof;

FIG. 3 is a rear perspective view thereof;

FIG. 4 is a left side view thereof;

FIG. 5 is a right side view thereof;

FIG. 6 is a top view thereof;

FIG. 7 is a bottom view thereof; and,

FIG. 8 is a rear, right, and bottom perspective view thereof. The broken lines in the figures are shown for the purpose of illustrating portions of the camera and/or environmental matter and form no part of the claimed design.

1 Claim, 8 Drawing Sheets
